CLAIM

The ornamental design for a multi-function printer, as shown and described.

DESCRIPTION

FIG. 1 is a top, right side perspective view of a multi-function printer embodying our new design;

FIG. 2 is a top, left side perspective view thereof in which driver's licenses are shown in broken lines, depicting one driver's license entering on the right and another existing on the left forming no part of the claimed invention;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

1 Claim, 4 Drawing Sheets
